Fig. 5

MATCHPLATE MOLDING MACHINE

This is a division of application Ser. No. 216,013, filed Jan. 7, 1972, now U.S. Pat. No. 3,794,103.

This invention relates generally as indicated to a matchplate foundry molding machine and more particularly to a machine of the type noted which is compact and of simplified operation.

Matchplate molding machines generally include a fill and molding station together with a closing station. In order to accomplish both fill and molding at the same station, it is normally required that the molding or squeeze head be laterally shiftable to clear the flasks therebelow for filling or that a sand measuring box be indexed into position for filling in the molding station. This generally requires either a horizontally movable squeeze head or a horizontally movable sand metering box or both. Examples of such matchplate molding machines may be seen in U.S. Pat. No. 3,589,432 to Miller et al and Hunter U.S. Pat. No. 3,406,738.

It is also desirable to have a matchplate molding machine wherein the tooling can be quickly changed. The tooling includes the matchplate which incorporates both the cope and drag patterns as well as the squeeze head which may imprint a pouring basin on the cope portion of the sand cake. With the machine of the present invention, both the matchplate and the squeeze head may be quickly changed. The present invention also provides a matchplate molding machine which utilizes a jolt mechanism in the squeeze head, the latter being vertically stationary and thus avoiding the complexities attendant to providing a jolt mechanism in the vertically movable squeeze table. The present invention provides a matchplate molding machine wherein the cope and drag are filled at one station and then moved to an adjacent molding station, the cope and drag being rammed at the molding station with the matchplate then being drawn first from the cope and then the drag, the latter being booked with the flasks lifted therefrom to form a booked cope and drag sand cake, the thus formed mold then being pushed from the molding station after the cope and drag flask is reassembled with the matchplate to be shifted to the fill station for filling.

It is accordingly a principal object of the present invention to provide a matchplate molding machine of a compact design wherein the molding, drawing, stripping and closing is all accomplished at the molding station.

Another important object is the provision of a compact matchplate molding machine utilizing adjacent fill and molding stations, the sand cakes being rammed, drawn, stripped and closed at the latter.

A further important object is the provision of a matchplate molding machine utilizing at the molding station unique cope and drag support means controlling the position of the cope and drag flasks following molding to obtain drawing, booking, stripping and reassembly.

A further object is the provision of a matchplate molding machine utilizing a fill station having sand fill apparatus which can quickly fill the drag and then the cope with measured amounts of sand.

Still another object is the provision of a matchplate molding machine utilizing a simplified hydraulically operated table to receive the sand filled cope and drag flasks and to ram the sand therein.

Yet another object is the provision of a matchplate molding machine utilizing a squeeze head incorporating a jolt ram therein.

A still further object is the provision of a matchplate molding machine utilizing a cope support permitting the cope to move upwardly but not downwardly until released for reassembly.

A yet further object is the provision of a matchplate molding machine having an improved matchplate indexing mechanism which operates during the cycle of the machine to index the matchplate both with and without the cope and drag flasks.

Other objects and advantages of the present invention will become apparent as the following description proceeds.

To the accomplishment of the foregoing and related ends, the invention, then, comprises the features hereinafter fully described, the following description and the annexed drawings setting forth in detail a certain illustrative embodiment of the invention, this being indicative, however, of but one of the various ways in which the principles of the invention may be employed.

In said annexed drawings:

FIG. 1 is a side elevation of a machine in accordance with the present invention;

FIG. 2 is a front elevation of the machine with the table operating piston-cylinder assembly and the squeeze head partially broken away and in section as seen from the line 2-2 of FIG. 1;

FIG. 3 is a rear elevation of the machine as seen from the line 3-3 of FIG. 1;

FIG. 4 is a vertical section taken through the fill station of the machine as seen from the line 4-4 of FIG. 1;

FIG. 5 is an enlarged elevation of the draw mechanism of the machine with one of the draw cylinders being shown in section;

FIG. 6 is an enlarged elevation of the bottom board feeding mechanism as seen in FIG. 4;

FIG. 7 is a top plan view of such bottom board feeding mechanism as seen from the line 7-7 of FIG. 6;

FIG. 8 is a fragmentary enlarged end view of the bottom board feed mechanism;

FIG. 9 is an enlarged end elevation of the matchplate indexing and carriage inversion mechanism;

FIG. 10 is an enlarged side elevation of the matchplate indexing and carriage inversion mechanism partially broken away and in section;

FIG. 11 is an enlarged end elevation of the matchplate indexing piston-cylinder assembly;

FIG. 12 is an axial section of such piston-cylinder assembly taken substantially on the line 12-12 of FIG. 11;

FIG. 13 is a fragmentary section taken substantially on the line 13-13 of FIG. 11;

FIG. 14 is a fragmentary top plan view of the mechanism shown in FIG. 10 as seen from the line 14-14 thereof;

FIG. 15 is an enlarged vertical section of the cope support mechanism;

FIG. 16 is a horizontal section taken substantially on the line 16-16 of FIG. 15;

FIG. 17 is an enlarged top plan view of the squeeze head;

FIG. 18 is a quarter section of the squeeze head taken substantially on the line 18-18 of FIG. 17;

FIG. 19 is a section of the squeeze head taken substantially on the line 19—19 of FIG. 17;

FIG. 20 is an enlarged section of the table supporting hydraulic piston-cylinder assembly;

FIG. 21 is an exploded assembly of the cope, matchplate frame and drag assembly;

FIG. 22 is a top plan view of the matchplate support frame;

FIG. 23 is a fragmentary detail section through the drag taken substantially on the line 23—23 of FIG. 21;

FIG. 24 is a time and motion chart showing the position of the draw rollers and table during a cycle of the machine;

FIG. 25 is a schematic illustration of the hydraulic components of the machine; and

FIG. 26 is a schematic illustration of the pneumatic components of the machine.

THE MACHINE - GENERAL ARRANGEMENT

Referring initially to FIGS. 1 through 4, it will be seen that the machine includes a base 10 elongated front to back which includes two laterally spaced longitudinally extending members 11 and 12 of rectangular section. At the front of the machine extending upwardly from the base are four columns 13, 14, 15 and 16. Such columns are interconnected at their top by a head frame 18. The head frame is provided with corner cylindrical projections 19 which are aligned with similar projections 20 on the base. The columns are of solid square section construction with cylindrical threaded portions 21 extending through the head and base and held in place by the large nuts indicated at 22 and 23.

Two additional columns 25 and 26 extend upwardly from the base near the rear of the machine and are interconnected at the top by structural tubular member 27. The member 27 extends between two longitudinally extending frame members 28 and 29 which are connected to the columns 13 and 16, respectively. The structural members 27-29 form a support frame somewhat below and to the rear of the head frame 18. The columns 13, 16, 25 and 26 enclose a fill station 3 while the columns 13, 14, 15 and 16 enclose a molding station 31.

Forming the top of the fill station 30 is a sand chute 33, the bottom of which is normally closed by arcuate blade or chop gate 34. Such blade is supported to project from the distal ends of arms 35 and 36 which are pivoted on pins 37 and 38, respectively, which are mounted in the apex of frames 39 and 40 which as seen in FIG. 1 are shaped rather like the letter K. Such side frames 39 and 40 are mounted on the longitudinal structural members 28 and 29, respectively.

The arms 35 and 36 extend beyond the pivot pins 37 and 38 to the front of the chute 33 and are interconnected by tubular member 42. The rod 43 of hydraulic piston-cylinder assembly 44 is connected to the transverse member 42 by the pin and clevis connection 45, the cylinder 44 being pivotally supported on fixed bracket 46. In this manner, retraction of the piston-cylinder assembly will cause the arms 35 and 36 to pivot to the phantom line position indicated at 48 in FIG. 1 withdrawing the blade 34 from the path of the chute 33.

This permits sand to fall against normally horizontally extending doors 50 and 51 which are pivoted at 52 and 53, respectively. Such doors in their horizontal position close the bottom of the sand chute 33. The doors

are opened and closed by means of piston-cylinder assembly 54. The cylinder of such assembly is fixed to bracket 55 and the rod is connected to links 56 and 57 which are in turn connected to relatively short crank arms 58 and 59, secured to the pivot shafts 52 and 53, respectively. Accordingly, extension of the piston-cylinder assembly 54 will cause the doors 50 and 51 to swing downwardly opening the bottom of the sand chute.

Such doors in their open position form a continuation of the front and back walls of sand chute extension 61. Positioned in such sand chute extension are sand aerators 62 and 63 of the configuration seen more clearly in FIGS. 1 and 4, such aerators being mounted on shafts 64 and 65, respectively. Such shafts are parallel and extend transversely through the chute extension. The shaft 64 is provided with a pulley 67 driven by belt drive 68 from the drive pulley 69 of drive motor 70. The shaft 65 is rotated at the same speed in the opposite direction by the gear transmission indicated at 71 in the housing 72.

Directly beneath the discharge opening 73 of the sand chute extension 61 is a rollover frame 75 which is designed to hold cope 76, matchplate 77 and drag 78 in assembled condition. In the normal position of such frame, the cope 76 is presented to the discharge opening 73 for filling and in the inverted position the bottom of the drag 78 will be presented to such discharge opening for filling.

The rollover frame includes a main U-shape support for the cope-matchplate-drag assembly as indicated at 79, such support being carried in cantilever fashion by spaced journals 80 and 81 seen in FIG. 1, the inner or rotating part of such journals being interconnected by tubular member 82 of the square section noted in FIG. 3. Such journals are supported on brackets 83 secured to tubular transverse frame member 84 extending between the columns 25 and 26. Inversion of the frame 75 is obtained by rollover piston-cylinder assembly 85, the upper end of which is pivoted at 86 to the frame while the rod is pivoted at 87 to laterally extending ears on the tubular extension 82. The rollover frame is shown in greater detail in FIGS. 9, 10 and 14.

Mounted on the support 79 and situated within the tubular extension 82 is a rather long stroke index piston-cylinder assembly 88 which is shown in greater detail in FIGS. 11, 12 and 13. The rod of the index piston-cylinder assembly is provided with a disc 89 on its end which is adapted to engage the matchplate frame as seen in FIGS. 21 and 22. Such index piston-cylinder assembly functions to shift the cope-matchplate-drag assembly from the fill station 30 to the molding station 31 when filled with sand, to retract the matchplate alone after the pattern has been drawn from the sand cakes, and to return the empty but assembled cope-matchplate-drag to the fill station after the cope and drag flasks have been lifted from the sand cakes and reassembled with the matchplate.

The term molding station for the station 31 is perhaps a misnomer by omission since at the molding station not only are the sand cakes molded in the cope and drag flasks, but also, the pattern or matchplate is drawn from the cope and drag, the drag may be cored if desired, the cope and drag sand cakes are booked, the cope and drag flasks are lifted or stripped from the sand cakes, the cope-matchplate-drag are reassembled, and the closed sand mold is pushed from the machine. The

components which enable this variety of functions to be obtained include a table 91 supported on the rod 92 of piston-cylinder assembly 93. The piston-cylinder assembly 93 is secured to a casting 94 supported in the base 10. The table includes a downwardly extending guide rod 95 which extends through a guide bushing 96 mounted in extension 97 of the support casting 94. The structure of the table and the details of the piston-cylinder assembly supporting the table are shown in better detail in FIG. 20.

Above the table 91 the molding station is provided with a roller support frame on each side as indicated at 99 and 100 in FIG. 2 on which are mounted a series of horizontally aligned support rollers indicated at 101 and 102, respectively. Such rollers are for support of the matchplate frame in the molding station. The roller support frame 99 is secured to the interior of the columns 13 and 14 while the frame 100 is secured to the interior of the columns 15 and 16. Each roller support frame is provided with a center U-shape outwardly offset portion as indicated at 103 to clear the stanchions seen at 104 and 105 which pendently support a U-shape draw frame 107. The draw frame includes parallel rails 108 and 109 on which horizontally aligned inwardly directed series of rollers 110 and 111 are mounted, respectively. The rails 108 and 109 are interconnected at one end by the transverse member 112 to complete the U-shape draw frame 107.

The upper ends of the stanchions 104 and 105 of the draw frame are secured to the rods 114 and 115 of vertically extending draw piston-cylinder assemblies 116 and 117, respectively. The draw piston-cylinder assemblies are supported at their lower ends on plates 119 and 120, such plates being secured to vertically extending plates 121 and 122, respectively, secured to the head frame 18. The draw piston-cylinder assemblies are thus supported at their lower end and extend upwardly through the head frame 18. The details of the draw frame and the piston-cylinder assemblies actuating the same are disclosed in greater detail in FIG. 5.

A cope support means is also provided in the molding station in the form of cope disc assemblies 125 which are horizontally aligned, two being provided on each side of the machine. Such disc assemblies comprise discs 126 and 127 separated by spacer 128. Each of the four horizontally aligned disc assemblies is secured to the bottom end of a respective vertically extending guide rod 130, such rods extending through vertically elongated guide sleeve 131. The lower ends of the guide sleeves on the right hand side of the machine seen in FIG. 2 are secured to the plate 120, the same plate supporting the lower end of the draw piston-cylinder assembly 117. The upper ends of the guide sleeves are secured to the head frame 18. The guide sleeves on the left hand side of the machine as seen in FIG. 2 are supported by the plate 119 at their lower end and similarly secured at their upper end to the head frame. Vertically extending rods 130 are interconnected at their upper end by a frame which includes two transverse bars 133 and 134 on which are secured vertically extending pyramid plates 135 and 136, the tops of which are interconnected by bridge plate 137. The bridge plate is connected at 138 to the rod 140 of piston-cylinder assembly 141, the blind end 142 of which is supported in the head frame 18. The construction of the piston-cylinder assembly 141 by which the

position of the cope disc assemblies 125 is controlled is seen more clearly in FIGS. 15 and 16.

Disposed centrally in the molding station and pendently supported from the head frame 18 is a pneumatic cylinder 144 in which is mounted reciprocably a jolt ram 145. The lower end of the cylinder 144 is provided with a frame 146 to which is removably secured squeeze board 147. The squeeze head and the manner in which it is supported from the head frame is shown more clearly in FIGS. 17, 18 and 19.

A mold push-off plate 150 is provided in the molding station which, when retracted, will be laterally adjacent the table in its lowermost position. The plate is connected to the rod 151 of long stroke piston-cylinder assembly 152 which is supported at its rod end on plate 153 extending between the columns 13 and 14. Also secured to the push-off plate is a guide rod 154 which extends through relatively short guide sleeve 155 mounted on the frame plate 153. An angle support bracket 156 extends from the plate 153 parallel to the rod 154. The vertical face of the angle may serve as a limit switch mounting plate with the switch actuator being carried on the end of the guide rod 154. With the table down, extension of the piston-cylinder assembly 152 will cause the completed mold to be pushed from the machine by the plate 150.

Also mounted on the same side of the machine as the mold push-off is a bottom board feeder shown generally at 160. The bottom board feeder includes a chute for a stack of bottom boards as indicated at 161 which are dealt from the bottom of the deck one at a time by the feeder mechanism to be inserted over the open end of the drag when the drag is inverted and after it has been filled with sand. The bottom board feeder 160 is shown in greater detail in FIGS. 6, 7 and 8.

In addition to the aerator motor the machine also includes a motor 164 mounted in sand shedding housing 165 at the bottom of the fill station, such motor driving hydraulic pump 166. Hydraulic fluid is supplied from reservoir 167 which is mounted at the top of the machine just behind the sand metering apparatus. The reservoir is connected to the pump and valve through piping indicated at 168 which includes manually operated shut-off valve 169. The hydraulic valves shown generally at 170 are mounted at the back of the machine on support bracket 171 supported by transverse framing member 172 extending between the longitudinal members 11 and 12 of the base 10. Also at the back of the machine there is provided the electrical cabinet 173 which includes safety disconnect switch 174. The operator's control panel is, however, mounted on the front of the machine as indicated at 175. When the machine is producing molds which require cores, the machine will stop just prior to closing so that the operator may place cores in the top of the drag sand cake. Before the machine can then close, the operator must push both control buttons 176 and 177, seen in FIG. 2, requiring that his hands and arms be clear of the molding station.

FIG. 5 - THE DRAW PISTON-CYLINDER ASSEMBLIES

Referring now to FIG. 5, it will be seen that the draw piston-cylinder assemblies 116 and 117 supporting the draw frame 107 each are comprised of two randomly arranged pneumatic piston-cylinder assemblies 180 and 181. The upper assembly 180 includes cylinder 182 extending between heads 183 and 184 with the pis-

ton 185 thereof being connected to the end of rod 114. The upper cylinder head 183 is secured to the lower or intermediate head 184 by tie rods 186.

The lower assembly 181 includes cylinder 188 extending between the intermediate head 184 and lower cylinder head 189. Tie rods 190 extend between the intermediate head 184 and the lower head 189. The piston 191 of the lower assembly 181 is secured by spanner nut 192 to axial cylindrical extension 193 of mounting piston rod 194. The lower end of such rod is provided with a flange 195 which is secured directly to the mounting plate 119 in turn secured to the frame of the machine. The mounting piston rod 194 is provided on its interior with guide bushings 196 and 197, the latter bushing being held in place by retainer 198. Accordingly, the hollow rod 194 and the piston 191 secured thereto are fixed with respect to the machine frame.

The lower cylinder head 189 includes a rod bushing 199 held in place by retainer 200 such bushing sliding over the polished outer surface of the mounting rod 194. The intermediate head 184 also includes a rod bushing 201 and cushion rings are provided as indicated at 202, 203, 204 and 205. The top cylinder assembly 180 is vented through its top through a muffler and similarly the bottom of the cylinder assembly 181 is vented through a muffler. Live air is supplied to the cylinders 182 and 188 through the ports 207 and 208, respectively, in the intermediate head 184.

The piston 191 fixed to the frame of the machine provides positive and accurate stops for several positions of the draw frame 107. In the operation of the machine it is critical that the draw frame 107 be positioned accurately to receive the drag flask of the cope-matchplate-drag assembly when it is indexed from the fill station to the molding station. This is accomplished with the lower head 189 abutting against the piston 191 as illustrated. It is also important to have a fixed position of the drag sand cake during coring and this is accomplished with the intermediate head 184 abutting against the top of the piston 191. When the rod 114 extends to its maximum up position, the piston 185 will engage the head 183 at the completion of the lifting of the cope and drag flasks from the sand cake. The position of the head 183 is, of course, controlled by the abutment of the lower head 189 against the fixed piston 191.

Since the rods of the piston-cylinder assemblies 116 and 117 are interconnected by the draw frame 107, such assemblies will act in unison. The draw frame 107, in addition to the sets of support rollers 110 and 111, which underlie respective rails on the drag flask, also includes downwardly extending buttons or projections 209 and 210 which overlie laterally extending projections on the drag flask. Thus upward pressure on the drag flask by means of the table 91 will also cause the rods 114 and 115 to move upwardly. The drag flask is accordingly confined in the draw frame at all times while in the molding station.

THE BOTTOM BOARD FEEDER - FIGS. 6, 7 AND 8

The bottom board feeder 160 is mounted on the side of the machine between the frame columns 25 and 13 and is adapted to feed bottom boards into the fill station to cover the open end of the drag flask after it has been filled with sand. The bottom board feeder is supported in cantilever fashion from the column 13 by

upper and lower L-shape frame members 220 and 221 seen in FIG. 8, the short legs of such frame members being secured to the column 13 by the fasteners indicated at 222. The top and bottom frame members are interconnected by a vertically extending plate 223. Secured to the column 25 is a vertically extending plate frame 225. Such plate frame includes inwardly projecting ears 226 to which are secured roller support bars 227. Projecting inwardly from the roller support bars are three horizontally aligned rollers 228, 229 and 230. There is also provided one or more upwardly projecting rollers indicated at 231 in FIG. 8. Projecting from the top of the frame plate 225 are roller support brackets 232 and 233 seen in FIG. 7 supporting downwardly projecting rollers 235 and 236 respectively. The two frames are secured together by transversely extending tie bars 238, 239 and 240.

The frame plate 225 support on its interior piston-cylinder assembly 242, the rod 243 of which is connected by pin 244 to lateral projections 245 and 246 extending from vertical web 247 supporting horizontally extending shuttle plate 248. The vertical web includes top and bottom rails 249 and 250 which are supported and confined by the rollers previously noted. The profile configuration of the horizontally extending shuttle plate 248 is perhaps best seen in FIG. 7 and includes two relatively thin transverse portions 251 and 252 and a rather narrow forwardly extending portion 253 on the side opposite the web which even in the fully retracted position of the shuttle underlies inwardly projecting roller 254 mounted on the vertical plate 223. The shuttle also includes bottom board engaging shoulders 255 and 256.

When the shuttle is retracted, a stack of bottom boards seen at 257 is placed in the chute 161 which is formed by the corner guides 258. The lowermost board is supported then on skid bars 259 and 260 which are supported from beneath by the respective side frames of the bottom board feeder. The lower end of the guides 258 is spaced above the skid bars a distance slightly more than the thickness of a bottom board. The shuttle plate 248, being slightly thinner than a bottom board, will then engage the lowermost bottom board in the stack at the shoulders 255 and 256 as the piston-cylinder assembly 242 indexes forward. The bottom board is then slid along the skid bars 259 and 260 beneath guide bars 262 and 263 into the inverted rollover frame 75 at the proper point in the cycle of the machine. The rollover frame is provided with a support roller 264 which will be horizontally aligned with the rollers 228, 229 and 230 when the frame is inverted as seen in FIG. 6. Limit switches 265 may be secured to the rail 249 to control the movement of the shuttle. A pipe guard 267 is provided to keep the area behind the shuttle clear.

ROLLOVER FRAME 75

Referring now to FIGS. 6, 9, 10 and 14, the main U-shape rollover frame 79 includes L-shaped arms 270 and 271 which are secured to frame base member 272 by the fasteners indicated at 273 in FIG. 14. Bridging the outer ends of the arms 270 and 271 is an arch-like frame 274 which supports cope strike-off 275 held in position by backup plate 276.

The interior of each arm is provided with two sets of horizontally aligned rollers as indicated at 277 and 278,

the latter being supported on rails 279 which project inwardly of the roller sets 277. The rollers 277 support the matchplate frame in the fill station and are horizontally aligned in the upright position of the rollover frame 75 with the rollers 101 and 102 in the molding station seen in FIG. 2. The rollers 278 in the rollover frame are horizontally aligned in the upright position with the rollers 110 and 111 on the draw frame when the latter is in its reception position in the molding station.

Also projecting inwardly from the arms 270 and 271 are L-shape brackets 280, there being two such brackets on each arm. Each bracket is provided with an adjustable hold-down button 281 adapted to overlie a projection on the cope when the latter is in the fill station to maintain the cope, matchplate and drag assembled when the rollover frame is inverted.

Secured to the base member 272 by the framing indicated at 283 are tines 284 and 285 which in the upright position of the rollover frame underlie the drag. Each tine includes two laterally projecting bottom board guides as seen at 286. Such guides have a sloping bottom edge, when inverted, adapted to guide the bottom board beneath such tines as seen in FIG. 6. The upper edge, when inverted, of both the guides and tines are pointed to shed sand.

As seen more clearly in FIG. 10, the base member 272 has secured thereto a bracket 288 on which is mounted arm 289 for sand probe 290. Mounted on the support framing 283 for the tine is a bracket 291 supporting arm 292, the distal end of which contains sand probe 293. The probe 293 is employed to signal the filling of the drag with sand while the probe 290 is employed to signal the filling of the cope with sand. The bracket 291 of the drag probe 293 is forwardly offset to clear the vertically extending web of the bottom board shuttle which will achieve the position 294 seen in phantom lines in FIG. 10 when the shuttle is extended. The roller 264 on which the bottom rail 250 of the shuttle is supported is mounted on an eccentric stud 295 so that the vertical elevation of the roller 264 may be adjusted.

The base 272 of the rollover frame is secured to the interior rotating portion 296 of the journal 81 which is in turn secured to the rearwardly extending tube 82. The rollover frame 75 is thus supported for inversion in cantilever fashion by the journals 81 and 80. Shields 297 and 298 are provided for the journal 81.

Inversion of the rollover frame is obtained by the piston-cylinder assembly 85, the rod 300 of which is connected by the pin 301 to the ears 302 and 303 projecting from the tube 82. Situated beneath the tube are two L-shaped supports 304 and 305 seen in FIG. 9 on which are mounted adjustable stops 306 and 307. These stops engage the opposite sides of projection 302 thus serving as stops for the upright and inverted position of the rollover frame. Limit switches are provided at 308 and 309 actuated by magnet 310 mounted on the tube 82. A limit switch 311 is also provided as seen more clearly in FIG. 10 mounted on bracket 312 secured to the cylinder of the piston-cylinder assembly 85. The limit switch 311 will be actuated by the magnet just before the position indicated in phantom lines at 313 in FIG. 9 or at approximately an 85° position. The tripping of the switch 311 shuts off hydraulic power and a special construction of the piston-cylinder assembly 85, which

includes a built in shock absorber, permits the rollover frame to continue to the end of its stroke.

The matchplate indexing piston-cylinder assembly 88 includes a front head 315 which is secured by elongated fasteners 316 directly to the base member 272 of the rollover frame. The head 315 is also supported at its rear end by centering screws 317 seen in FIG. 9 extending through washer and nut assemblies secured to the walls of the tube as indicated at 318.

10 THE MATCHPLATE INDEXING CYLINDER ASSEMBLY

Referring now to FIGS. 11, 12 and 13, the matchplate indexing piston-cylinder assembly 88, in addition to the front head 315, includes a rear head 320 with cylinder 321 extending between the heads and secured thereto by the threaded connections seen at 322. A piston 323 is secured to piston rod 324 by the nut and washer assembly 325. The rod extends a substantial distance rearwardly beyond the piston and is provided at its rear end with a pilot or cam surface 326 which in the full rearward position of the rod will actuate spring loaded limit switch plunger 327. The plunger is mounted on the rear head 320 by the fasteners indicated at 328. The rear head 320 is provided with a coaxial type port 329.

Fore and aft the piston 323, the rod 324 is provided with cushion rings 330 and 331, respectively. Such cushion rings operate in conjunction with bypass passages which include check valves 332 and 333. Such check valves operate to permit the hydraulic pressure to bypass the cushion rings to act directly upon the piston 323 at the initiation of the stroke.

The head 315 is provided with a rearwardly extending pipe port 335 which communicates with annular passage 336. Forwardly of the front cushion ring 330, the rod 324 is provided with a shallow annular groove or depression 338 which in the forwardmost position of the rod 324 will actuate spring loaded ball plunger 339 mounted in the front head 315 by the fasteners 340. The front of the head 315 is provided with a gland 342 secured by fasteners 343. The head 315 also includes the tapped holes 344 for the fasteners 316 seen in FIG. 10. The front of the rod 324 is provided with an internally threaded socket 345 to permit the disc 89 to be secured thereto.

Reverting briefly to FIGS. 9 and 10, the plunger 327 on the rear cylinder head 320 actuates limit switch 347 mounted on bracket 348 while the plunger 339 actuates limit switch 349 mounted on a bracket, not shown, secured to the tube 82. Thus the plunger 339 projects through such tube. Such limit switches, of course, oscillate with the cylinder and, of course, the rollover frame.

THE COPE DISC CYLINDER

Referring now to FIGS. 15 and 16, the cope disc piston-cylinder assembly 141 includes cylinder 350 in which the rod 140 is situated, such rod constituting the piston of the piston-cylinder assembly. The cylinder 350 is supported between the lower cylinder head 142 and upper cylinder head 351. Such cylinder heads also support an outer cylindrical housing 352 which forms with the inner cylinder 350 an oil reservoir 353. The cylinder heads may be held together by tie rods 354 seen in FIG. 16.

The lower cylinder head 142 is provided with a check valve 356 held in place by retainer 357 which permits flow only through the passages 358, the check valve and vertical passage 359 from the reservoir to the bottom of the piston. As the piston 140 is elevated oil will be drawn readily through the passages noted and the check valve but it cannot flow reversely back from the bottom of the piston to the reservoir.

The passage 359 leading to the bottom of the piston is, however, also connected to the reservoir through passages 361 and 362 in manifold 363 which is connected to the cylinder head 142 by the fasteners indicated at 364 in FIG. 16. Mounted on top of the manifold above the head frame 18 interconnecting the passages 362 and 361 is a sandwich type flow control valve 365 and a two position four way directional control valve 366. A fill pipe 367 is secured to the upper head 351 and is connected to the vertically extending pipe 368 in the reservoir 353 by the passage 369 in such upper head. This limits the extent to which the reservoir 353 can be filled.

As the rod or piston 140 is moved upwardly, it will freely draw oil from the reservoir 353 through the check valve 356 but the check valve precludes oil passing backwardly from beneath the piston into the reservoir. Thus as the cope achieves a certain elevation during the cycle of the machine, it will be held in such vertical position. Only when the solenoid operated control valve 366 is energized will the fluid be permitted to return from beneath the piston to the reservoir through the passages 361 and 362 at the rate controlled by the flow control valve 365. In this manner the cope disc cylinder assembly 141 acts as a ratchet freely permitting upward movement of the cope discs and thus the cope but permitting downward movement only when released by the solenoid operated control valve 366.

THE SQUEEZE HEAD

Referring now to FIGS. 17, 18 and 19, it will be seen that the squeeze head is supported from the head frame 18 by four support rods 370, 371, 372 and 373, vertically spaced projections 374 and 375 at each corner of the squeeze head, each projection being provided with a liner or bushing as shown at 376. The lower end of each support rod is provided with a nut and washer assembly 377 and a compression spring 378 surrounds each support rod between the nut and washer assembly and the lowermost projection 375.

The cylinder 144 is provided with an integrally formed bottom head 380 and a top head 381 is secured to the cylinder by fasteners 382. A FABREEKA or like material pad 383 is secured to the top of the head 381 by fasteners 384. In the static condition of the head a slight clearance is provided between the pad and the plate 385 underlying the head 18, the latter being provided with recesses 386 to clear the fasteners 384.

Within the cylinder 144 is mounted the jolt ram 145 which is provided with a center bottom nose 388 adapted to strike the center of the bottom head 380 which is formed integrally with the cylinder 144. Reciprocation of the ram is obtained by air admitted through the port 389 and exhausted through port 390 when the ram has achieved a slight elevation. The chamber above the ram optionally can be connected through port 391 to a suitable air spring so that the pressure above the ram may be controlled to facilitate the driving of the ram downwardly for the jolt strike. Alternating

tively the port 391 may be plugged with the air above the ram expanding and contracting, the pressure thus created facilitating the driving of the ram downwardly for its strike.

5 The squeeze board 147 is supported beneath frame 146, the latter comprising support bars 393 and 394 which are held to the bottom head 380 by the elongated fasteners 395. The squeeze plate or board 147 is provided with four upstanding L-shape support ears 396, the short legs of which overlie support locators 397 mounted on the interior walls of the bars 393 and 394. Peen strips 398 are held against peen sheet 399, both being secured to the squeeze board by fasteners 400. With the use of the support locators and ears 396 and 397, one man can readily change the squeeze board of the machine. The squeeze board may be provided with certain pattern features such as pouring basin projection 401 as seen in FIG. 18.

THE TABLE PISTON-CYLINDER ASSEMBLY

Referring now to FIG. 20, the table piston-cylinder assembly includes the rod 92 connected to the table 91, such rod having piston 405 secured thereto by nut 406. The rod 92 is hollow and projects over stationary piston rod 407 having piston 408 on the top thereof. The internal rod 407 is provided with a vertical passage 409. The lower end of the stationary internal rod is secured by the threaded connection 410 to retainer 411 secured by fasteners 412 to the bottom of cylinder head 413. The bottom cylinder head 413 is a two part construction, such parts being held together by tie rods extending through the apertures 414. The cylinder 93 extends between the lower head 413 and the upper head 415 secured by fasteners 416 to the lower end of annular center portion 417 of the frame 94. A relatively large bushing 418 is provided in the frame center portion 417. A seal 419 is held in place above the bushing by retainer 420, the latter supporting a wiper 421 riding against the O.D. of the rod 92.

40 A port 423 is provided at the bottom of the interior rod 407 for supplying oil to the relatively small chamber 424 above the piston 408. The lower head 413 also includes a somewhat larger port 425 which supplies oil to the chamber beneath the piston 405. The piston rod beneath the nut 406 is provided with an extension 426 which acts as a cushion ring. When such extension enters the cylindrical portion 427 of the head, it requires oil to flow through the restricted passage 428 slowing the descent of the table near the end of its stroke.

45 Initially to elevate the table, oil will be supplied through the port 423 into the relatively small volume chamber 424 causing the table 91 to rise. This draws oil through the port 425 beneath the piston 405. During the squeeze, pressure will be supplied through both ports. Accordingly, the port 425 is connected to the pump output only during squeeze and at other times is connected directly to tank. The position of the tank on the top of the machine as seen in FIG. 1 facilitates this mode of operation of the table piston-cylinder assembly.

55 As an example of the relative dimensions, it may be noted that in the illustrated embodiment a bore of the cylinder 93 is $4\frac{3}{4}$ inches while the O.D. of the rod 92 is $4\frac{1}{2}$ inches. The bore in the rod 92 is 2 inches while the O.D. of the rod 407 is $1\frac{3}{4}$ inches.

60 Also as illustrated perhaps most clearly in FIG. 20, it will be seen that the table 91 is provided with a plate

430 underlying diaphragm 431 which is peripherally secured to such underlying plate by top plate 432. Such top plate is provided with a circular opening 433 which permits the diaphragm to achieve the dome-like configuration indicated at 434 when inflated. During the molding operation, the bottom board beneath the drag sand cake may obtain a slight set, i.e. may be slightly out of a horizontal plane. During the draw and stripping of the cope and drag flasks from the sand cakes, the inflation of the rubber diaphragm provides the proper support to prevent the sand cakes from cracking or being damaged.

THE COPE-MATCHPLATE-DRAG ASSEMBLY

Referring now to FIGS. 21, 22 and 23, it will be seen that the cope 76 includes a rectangular top opening 436 into which the squeeze plate 147 is adapted to telescope. The squeeze head may telescope to approximately the extent of the vertical portion 437 of the wall of the cope flask, the remaining lower portion of the wall being tapered as indicated at 438. Projecting laterally from the top lateral edges of the cope are four projections 439 which fit rather closely between the discs 126 and 127 of the disc assemblies 125. Also projecting laterally from the bottom edge of the cope are four projections 440 adapted to underlie the button 281 on the brackets 280 in the fill station. This maintains the cope assembled with the matchplate as the assembly is inverted in the fill station for the filling of the drag. The cope is also provided with guide bushings 441 at opposite corners thereof which receive guide pins indicated at 442 and 443 projecting upwardly from the drag.

The matchplate 77 is supported on matchplate frame 445 seen in greater detail in FIG. 22. The frame is rectangular and has secured thereto the matchplate 77 by four suitable accessible fasteners 446. Such fasteners extend through projections on the matchplate as indicated at 448 which overlie the laterally extending matchplate frame portions 449 and 450. Such lateral extending frame portions are provided with vertically offset hump portions 451 which terminate at the ends of rails 452 and 453. Such rails have a flat bottom surface 454 which are adapted to engage roller sets 101 and 102 in the reception position in the molding station and the roller sets 277 in the fill station.

The matchplate frame includes a U-shape socket member 456 having face plate 457 secured thereto by the fasteners 458. The face plate is provided with a key-hole shape cut-out 459 opening at the bottom edge thereof to accommodate the stem 460 of disc 89 which is secured to the rod of the matchplate index piston-cylinder assembly 88. When the matchplate frame is supported on the rollers previously noted, the disc 89 is within the socket provided and extension and retraction of the matchplate index piston-cylinder assembly will index the matchplate frame and thus the matchplate either alone or with the cope and drag assembled thereto. The cut-out portion 459 in the plate 457 permits the matchplate frame to be elevated.

An air coupling 462 is connected to port 463 on the matchplate frame. The port 463 is connected through piping 464 to vibrator 465 mounted on stanchions 466 and 467 on the matchplate frame. The matchplate frame includes guide bushings 468 and 469 aligned with the guide pins 442 and 443 projecting upwardly from the drag.

The drag 78, like the matchplate frame, includes horizontally extending rails 471 and 472 at the lateral upper edges thereof adapted to overlie roller sets 110 and 111 in the molding station and roller sets 278 in the fill station. It is these rails which extend beneath the offset portions 451 of the matchplate frame in the assembled condition of the cope, matchplate and drag. The drag also includes four lateral projections 473 which underlie the buttons 209 on the draw frame rails 108 and 109. In this manner, the drag in the molding station is confined by the draw frame and moves therewith.

The interior wall of the drag includes the tapered upper portion 474 and a vertical lower portion 475 into which the bottom board is adapted to be telescoped during squeeze. Secured to the bottom outside edge of one side of the drag are two L-shaped stop brackets 476 which include V-shape projections 477 beneath the drag. The front and rear bottom edges of the drag are also provided with guide projections seen at 478. The guides 478 serve as lateral guides for the bottom board as it is slid over the inverted drag against the stops 477. The bottom board will act as a drag strike-off, the V-shape configuration of the stops precluding sand from being compacted thereagainst. It is also noted that the top edge of the cope indicated at 479 is quite thin to facilitate the shedding of sand. In fact, where possible, substantially all of the surfaces which may receive loose or falling sand are sloped to facilitate sand shedding.

As an optional feature, the underside of the matchplate frame 445 may be provided with depending elongated brackets 480 having throughbores 481 therein adapted to receive electrical heating elements.

THE HYDRAULIC CONTROLS

Referring now to FIG. 25, it will be seen that the pump 166 driven by motor 164 draws hydraulic fluid from the reservoir 167 through line 485 and filter 486, the output of the pump proceeding through lines 487 and 488 which are connected to manifold lines 489 and 490, respectively, through relief valves 491 and 492. The two manifold lines 489 and 490 are interconnected by safety relief valve 493 and it is to these manifold lines that the control valves 494, 495, 496, 497, 498 and 499 are connected, such valves operating the mold push-off cylinder assembly 152, the sand door cylinder assembly 54, the sand chop gate cylinder assembly 44, the matchplate index cylinder assembly 88, the bottom board feeder cylinder assembly 242, and the rollover cylinder assembly 85, respectively. The valves 494, 495, 496, 498 and 499 are single solenoid two position valves, while the valve 497 is a double solenoid three position valve.

The direction of the table 91 is controlled by the double solenoid three position valve 501. The speed of the table in descent is controlled by double solenoid three position valve 502, flow control valves 503 and 504, flow control valve 505 and relief valve 506. High pressure squeeze is obtained by energizing solenoid operated two position valve 508.

When solenoid 510 is energized, the output of the pump is connected from line 511 to line 512 which leads both to the squeeze control valve 508 and through line 513 to the port 423 beneath the stationary rod 407. As the table initially elevates, hydraulic fluid will be drawn beneath the larger piston 405 through the

line 514 from the reservoir 167. For squeeze, the solenoid 510 will be energized simultaneously with the solenoid of the valve 508 connecting the output of the pump to both lines 513 and 514. A decompression relief valve and flow control is provided bypassing the squeeze control valve 508 as indicated at 515. A pressure switch 516 will energize the squeeze valve 508 to start the squeeze cycle. With the three position valve 502, three table down speeds may be obtained. With the valve in its center or closed position, oil is forced through the adjustable flow control 505 to obtain a draw speed. With the solenoid 518 energized, the hydraulic oil passes through flow control 503 to obtain a full down table speed. With the solenoid 519 energized, the oil passes through the flow control 504 to obtain a drift down speed, the latter being employed to obtain precise table height for reception of the sand filled cope-matchplate-drag assembly.

To position the matchplate in the fill station, the solenoid 520 is energized and to position the matchplate in the molding station, the solenoid 521 is energized. As will be set forth more clearly hereinafter, each of such solenoids will be energized twice during the cycle of the machine. The solenoid 522 operating the rollover cylinder assembly 85 will be energized to retract such assembly and will be deenergized just before the midpoint of the rollover by the limit switch 311 seen in FIG. 10. This shuts off the pump pressure to the rollover cylinder and the spring 523 in the cylinder and the inertia of the carriage causes the piston to extend completing its stroke.

Air pressure is supplied to the top of the reservoir 167 from source 524, such air pressure being quite low and being relieved by relief valves 525 as the oil volume fluctuates.

THE PNEUMATIC CONTROL SYSTEM

Referring now to FIG. 26, the upper cylinder assembly 180 of each of the draw piston-cylinder assemblies 116 and 117 is operated by a three position double solenoid valve 530 supplying air from source 531 selectively to line 532 or 533, both being connected to pilot operated two position control valve 534. The line 533 is provided with a pressure regulator 535. Accordingly, pressure may be supplied through line 536 to the rod end of each of the upper cylinder assemblies 180 at line or regulated pressure. The regulated pressure will obtain during squeeze permitting the draw frame to follow upwardly with the table.

The lower draw cylinder assemblies 181 are controlled through two position solenoid control valve 537 supplying air to or venting the upper end of such cylinder assemblies through flow control valve 538 in line 539.

The control of the jolt ram 145 and the vibrator 465 on the matchplate frame is obtained by two solenoid three position valve 540 supplying air pressure to line 541 or 542 at the proper point in the cycle of the machine. In the center position of the valve, both lines are vented.

A pattern blow-off indicated at 545 and a pattern spray indicated at 546 are controlled by solenoid operated poppet valves 547 and 548, respectively, the spray being provided from liquid pressure tank system 549. In addition, a sprue-cup blow-off indicated at 551 may be provided controlled by solenoid operated poppet valve 552. Such valve operates to supply air to the

blow-off through pressure regulator 553. A similar solenoid operated poppet valve 554 supplies air pressure to the diaphragm dome 434 in the table 91 through line 555 and again a pressure regulator is provided at 556.

Although the solenoid operated valve 366 which releases the cope disc cylinder assembly 141 for lowering at the rate controlled by the flow control valve 365 is illustrated in FIG. 26, it is noted that such controls are not actually part of the pneumatic schematic.

The various solenoids illustrated are operated in the proper sequence by conventional timers and electrical interlocks.

OPERATION

Referring now additionally to FIG. 24, it will be appreciated that the cycle starts with the cope-matchplate-drag assembly in the fill station 30 and held in such assembled condition in the rollover frame 75. At the beginning of the cycle, the blade or chop gate 34 is closed and a metered amount of sand is on top of the doors 50 and 51. The rollover frame is now inverted to roll up the drag and the doors 50 and 51 are opened to fill the drag. The doors are immediately closed and as soon as they are closed the chop gate 34 is opened and then closed to prepare another sand charge. With the drag up and filled, the bottom board piston-cylinder assembly 242 is indexed forward to strike off the drag and to insert the bottom board. As soon as the bottom board shuttle is retracted, the cope is rolled up and the doors 50 and 51 again opened to fill the cope with sand. If the cope or drag sand probes indicate that for some reason one or the other was not filled with sand, the cycle will not proceed since the machine could damage the tooling if either the cope or drag were improperly filled.

During the filling of the drag, the insertion of the bottom board, and the filling of the cope, the table 91 has commenced elevation through energization of the valve 501 as seen at 560 in FIG. 24. When the table reaches the elevation indicated at 561, a limit switch energizes solenoid 517 of valve 501 and 519 of valve 502 to bring into operation drift down flow control valve 504. The table will then drift down relatively slowly a short distance indicated at 562 until a limit switch centers valve 501 holding the table precisely at reception elevation 563. The draw rollers 110 and 111 are at their reception elevation 564 as determined by the abutment of the lower head 189 with the fixed piston 191, pressure having been supplied to the lower piston-cylinder assembly 181 through the valve 537.

The filled flask assembly with the bottom board in place is now indexed onto the molding table 91 which has been raised to its reception height. This is obtained by the extension of the piston-cylinder assembly 88. When in proper position as determined by the forward limit switch 349, the table is elevated by the energization of the valve 501. Since in the reception position the cope is confined by the cope disc assemblies 125 and the drag is trapped by the draw frame, the matchplate frame being free to move upwardly, elevation of the table will elevate the draw frame and the cope disc assemblies. Regulated pressure may be applied at this point to the upper cylinder assemblies of the draw piston-cylinder assemblies to provide a pneumatic counterbalance to help in the lift. As soon as the table starts up for the squeeze, the jolt action is commenced by the valve 540.

The initial upward movement of the table at the commencement of the squeeze operation as indicated at 565 may be obtained only by the directional valve 501 and when resistance is encountered as indicated at 566, pressure switch 516 may be set then to shift the squeeze valve 508. The squeeze and jolt continue to the point 567 whereupon the table lowers, the speed of the table descending at 568 being controlled by flow control valve 505 through relief valve 506. At this point, the weight of the draw frame and cylinders may actually assist in pushing the table down. At this point the dome 434 is inflated and remains inflated until the cakes are free of the flasks.

Since the cope disc assemblies are precluded from lowering by the check valve 356 as the table initially lowers, the drag and matchplate are drawn from the cope which is held against the squeeze board by such cope disc assemblies. At the beginning of the draw, the vibrator 465 for the matchplate may be energized. When the drag and matchplate reach the matchplate rollers 101 and 102, the matchplate is drawn from the drag with the drag continuing down to coring height which is determined by the abutment of the intermediate head 184 against the fixed piston 191. This coring height is illustrated at 569 in FIG. 24. At this point, the matchplate, disassembled from the cope and drag, indexes to the fill station by retraction of the indexing piston-cylinder assembly 88. At this point the operator may set cores if required and to continue the cycle of operation, he must then press buttons 176 and 177 seen in FIG. 2. The draw cylinders now lift the drag as indicated at 570 while the table follows as indicated at 571 with its dome 434 still inflated. At the point 572 the drag contacts the cope held by the cope disc assembly. With the cope sand cake held by the squeeze board, the draw frame continues up to lift the flasks off of the booked sand cakes which are then supported by the table. The cope disc assemblies, of course, continue upwardly. After the cakes are free of the flasks, the dome 434 is deflated.

The sand cakes on the table are now lowered completely as indicated at 573. The cope remains held up by the cope disc cylinder assembly and the drag is lowered on the draw frame by the draw cylinders to the position 574 to clear the incoming matchplate which is now indexed back from the fill station to the molding station. At this point, the valve 537 is actuated as is the valve 366 seen in FIG. 26. The draw frame elevates to reception height 564 as determined by the fixed position 191. The cope discs simultaneously lower with the cope flask to again form an assembly of the cope, matchplate and drag. Such assembly is then again indexed to the fill station and the finished sand cake is pushed out of the molding station by the mold push-off.

The embodiments of the invention in which an exclusive property or privilege is claimed are defined as follows:

1. A foundry molding machine comprising a vertically movable table adapted to support a sand filled flask having a pattern therein, a squeeze head thereabove, a piston-cylinder assembly supporting said table for movement, said assembly including smaller and larger concentric pistons, means to supply fluid pressure to the smaller piston initially to elevate the table, the elevation of the table drawing fluid beneath the larger piston, and means to supply fluid pressure to both pistons to obtain high pressure squeeze.

2. A machine as set forth in claim 1 wherein said smaller piston is mounted on a fixed rod extending concentrically through said larger piston.
3. A machine as set forth in claim 2 including a tubular rod for said larger piston supporting said table and telescoping over said fixed rod.
4. A machine as set forth in claim 1 including a fluid reservoir for said piston-cylinder assembly positioned thereabove to facilitate the drawing of fluid beneath the larger piston.
5. A machine as set forth in claim 4 including valve means for said larger piston selectively to connect the same to said reservoir or to a source of fluid under high pressure.
- 15 6. A foundry molding machine having a vertically movable table and power means operative to raise said table for squeezing the sand within such flask to form a foundry mold, and lower said table to draw the pattern from the mold, characterized in that said table is supported on a hollow rod projecting from a cylinder, a piston on the lower end of said hollow rod forming a first chamber therebelow, a second rod projecting into said hollow rod through the lower end of said cylinder, a piston on the top of said second rod forming a second chamber thereabove, respective passages connected to said first and second chambers, said power means initially supplying pressure to one of said chambers to elevate said table thus to draw fluid into the other of said chambers, and then supplying pressure to both chambers to obtain squeeze.
- 20 7. A foundry molding machine as set forth in claim 6 wherein said second rod is stationary and the passage to such second chamber extends concentrically therethrough.
- 25 8. A machine as set forth in claim 6 including a fluid reservoir above said table to facilitate the drawing of fluid into the other of such chambers.
- 30 9. A machine as set forth in claim 6 including valve means alternatively connecting the other of such chambers to said power means or a fluid reservoir.
- 35 10. A foundry molding machine comprising a vertically movable table adapted to support a sand filled pattern containing flask, a squeeze head thereabove, a draw frame, means on said draw frame interengaging such flask to retain the flask for movement therewith, and piston-cylinder means for vertically moving said draw frame, said piston-cylinder means including fixed stop means for accurately vertically positioning said draw frame and thus the flask in a plurality of vertical positions.
- 40 11. A machine as set forth in claim 10 wherein said piston-cylinder means includes two interconnected cylinders, a piston in one connected to said draw frame, and a piston in the other fixed to the machine.
- 45 12. A machine as set forth in claim 11 wherein said cylinders are tandemly connected and concentric, said piston in one being connected to said draw frame by a rod extending concentrically through the other and its fixed piston.
- 50 13. A foundry molding machine comprising a vertically movable table adapted to support a sand filled flask having a pattern therein, a squeeze head thereabove, means for elevating said table to squeeze the sand in such flask, support means for holding such flask in the position achieved at the completion of the squeeze so that the lowering of the table will draw the pattern from the mold, said support means comprising
- 55 65

a hydraulic piston-cylinder assembly and a reservoir, and check valve means interconnecting the same to permit fluid to flow from the latter to the former but not vice versa.

14. A machine as set forth in claim 13 including control valve means also interconnecting said piston-cylinder assembly and said reservoir to bypass said check valve in response to operation of said control valve means.

15. A machine as set forth in claim 13 wherein said reservoir is in the form of a cylinder surrounding the cylinder of said hydraulic piston-cylinder assembly.

16. A machine as set forth in claim 13 wherein said piston-cylinder assembly extends vertically, and flask retaining means mounted on the rod of said piston-cylinder assembly operative to confine such flask for vertical movement therewith.

17. A machine as set forth in claim 16 wherein said

flask retaining means comprises sets of vertically spaced lateral projections which receive therebetween a lateral projection of the flask.

18. A machine as set forth in claim 17 wherein said sets are each mounted on vertically extending guide rods connected to the rod of said piston-cylinder assembly.

19. A machine as set forth in claim 17 wherein said sets of vertically spaced lateral projections comprise discs with a spacer therebetween.

20. A machine as set forth in claim 13 wherein said piston-cylinder assembly extends vertically with the rod projecting upwardly, said check valve means being connected to the blind end of the cylinder.

21. A machine as set forth in claim 20 wherein said reservoir is cylindrical and concentric with the cylinder.
